MOLDING FOR A DESK OR SIMILAR ARTICLE

Pehr J. Anderson, St. Charles, Ill., assignor to All-Steel Equipment Inc., Aurora, Ill., a corporation of Illinois

Filed July 5, 1960, Ser. No. 61,237

Term of patent 14 years

(Cl. D13—6)

The dominant features of the design reside in the portions shown in full lines on the drawings.

The dotted lines indicating portions of a desk in FIGS. 1 and 2 are for illustrative purposes only.

I claim:

The ornamental design for a molding for a desk or similar article, substantially as shown and described.
